US0D1082604S

(12) United States Design Patent (10) Patent No.: US D1,082,604 S
(45) Date of Patent:  Jul. 8, 2025

(54) PLANTER

(71) Applicant: Takasho Co., Ltd., Kainan (JP)

(72) Inventor: Nobuo Takaoka, Kainan (JP)

() Term: 15 Years

(21) Appl. No.: 35/519,074

(22) Filed: Nov. 21, 2022

(80) Hague Agreement Data

Int. Filing Date: Nov. 21, 2022

Int. Reg. No.: DM/225202

Int. Reg. Date: Nov. 21, 2022

Int. Reg. Pub. Date: Nov. 24, 2023
